ATTORNEY

UNITED STATES PATENT OFFICE.

OLIVER MITCHELL, OF BROOKLINE, MASSACHUSETTS.

FOUNTAIN PEN.

1,416,302.

Specification of Letters Patent. Patented May 16, 1922.

Application filed September 23, 1921. Serial No. 502,616.

To all whom it may concern:

Be it known that I, OLIVER MITCHELL, a citizen of the United States, residing at Brookline, in the county of Norfolk and 5 State of Massachusetts, have invented certain new and useful Improvements in Fountain Pens, of which the following is a specification.

My invention is an improvement in fountain pens and consists in the provision at the rear of the fountain or barrel of such a pen, of a means for withdrawing air from the barrel to a compartment at the upper end of the barrel, thus rarifying the air in the barrel 10 and causing an inflow of ink at the forward end of the barrel by the outer atmospheric pressure and later discharging the air from the upper compartment through a pipe leading from the upper compartment to the pen 15 end of the barrel. This operation is repeated as often as may be necessary to empty the barrel of air and fill the barrel with ink.

In the drawings:

Figure 1 is a longitudinal sectional elevation, broken, of a fountain pen embodying my improvement, showing the interior parts as at the end of the air expelling stroke;

Figure 2 is a partial longitudinal elevation, partly in section, showing the interior 30 parts at the end of the air-rarifying stroke;

Figure 3 is a cross-sectional view on line 3—3 of Figure 1;

Figure 4 is a cross sectional view on line 4—4 of Figure 1;

Figure 5 is a cross sectional view on line 5—5 of Figure 1;

Figure 6 is a longitudinal elevation, partly in section, of a modification.

The mechanism of my improved pen is of 40 the simplest. The fountain 1 carries at one end the feed bar 2 having ink feeding fissures 3 and a pen point 4, as is usual. The ink feed bar has, in addition to the ink fissures 3 another passage 5, which at its inner end is central of the bar and fountain, that is, corresponds with the longitudinal axis of the fountain and is connected with a pipe A extending axially of the fountain to near the top or rear end of the same.

50 Slidably fitting at the rear upper end of the fountain is a cup or chamber B, and

within this chamber and frictionally engaging the same, is a disk C which is mounted upon the pipe A and has preferably slight capacity for motion to and fro along that 55 pipe, between stops a, a'. A packing c' at the edge of disk C gives an air-tight frictional engagement with the inner walls of cup B.

There is provided between the cup B and the fountain 1 a suitable gland D which screws along the fountain to compress a packing, d, between the gland D and a shoulder d' formed in the upper inner end of the 60 fountain. Preferably in the closed end of 65 the cup B, I provide a vent hole normally closed by a screw plug, b, and at the open end of the cup a gland b' to compress a packing b'' between the cup and the fountain.

Preferably on the interior surface of cup 70 B, I provide a slot or slots E and also a stop or stops, e, so placed as to engage the disk C when the slots are opposite the edge of disk C, the length of the slots being such as 75 just to provide an air passage or passages around the disk C from one side to the other of the disk.

Through the upper end of pipe A just beneath the cap or stop, a, are preferably formed one or more holes a² communicating 80 with the interior of pipe A.

The preferred operation is as follows:

The parts being assembled as shown in Figure 1, to fill the pen, the pen end of the fountain is submerged in ink. The operator 85 holding the fountain with one hand, grasps the plug b, which serves as a finger piece at the outer end of cup B, with the other hand and draws the cup outward. The first effect of this action is to shift the disk C upward, 90 on pipe A, by the frictional engagement of disk C and cup B, thus closing the holes a² in pipe A (see Fig. 2). The cap or stop, a, limits the upward movement of disk C and continued movement of cup B enlarges the 95 space above disk C, while disk C prevents air from passing from fountain 1 to relieve the partial vacuum thus formed, and also prevents any relief of the partial vacuum through the pipe A and holes a², since holes 100 a² are closed by disk C on the initial movement of cup B outward.

The continued withdrawal of cup B continues, the air becoming more and more rarified, until slots E open a passage around disk C, stops e engaging disk C at this time and 5 preventing further movement outwardly of cup B.

As soon as slots E permit it, air from the fountain 1 passes by the disk C to the cup B, thus producing a sudden rarification of 10 air in the fountain 1 and causing atmospheric pressure to become suddenly effective to force ink through fissures 3.

The cup B is now pushed inward. The first effect of this action is to shift the disk 15 C downward, on pipe A, by the frictional engagement of disk C and cup B, thus opening the holes α^2 in pipe A (see Fig. 1). The stop α' limits the downward movement of 20 disk C and movement of cup B also pushes the slots E below the edge of disk C thus closing the passages for air around the edge of the disk through slots E, which were 25 opened upon the up stroke of cup B and simultaneously diminishing the space above disk C, forcing the air in cup B through holes α^2 , pipe A and passage 5, to the outer air. These operations are repeated until the 30 fountain is filled with ink, which will be indicated to the operator by the gradual decrease of ejected air bubbles at the immersed end of the fountain. When the bubbles begin to diminish the operation of the cup B should immediately cease.

It will be obvious that in filling a fountain 35 pen through the pen end, by atmospheric pressure, there are two conflicting conditions. It is desirable that the ink passages should be relatively large in order that ink may flow inward through the ink passages 40 freely and easily; it is also desirable that the ink passages should be only of capillary size, in order that as the fountain gradually empties, ink may not flow out through the ink passages by gravity or "flood". In my 45 improved pen I reconcile these conflicting requirements. My ink passages are fissures of capillary dimension easily retaining ink, against gravity, but, in filling, by applying an accumulated suction tension suddenly I 50 am enabled to force ink freely through the ink fissures.

The rarification of the air at each stroke will be governed by the position of the 55 grooves governing the passage of air from the fountain to the suction chamber. If, for example, the grooves were near the lower end of the cup, the stroke would be longer, the rarification within the cup greater and the sudden rarification in the fountain 60 greater when connection was made through the slots between cup and fountain, the result being a sudden and maximum application of atmospheric pressure to force ink into the barrel. It is obvious that, within

limits, this ink moving air pressure may be 65 governed as desired by providing for a desired length of movement by the cup.

I have shown and described the preferred form of my device and have described above, the preferred mode of operation. I do not, 70 however, limit myself to this preferred form or mode of operation, as, by simply leaving the upper end of pipe A open at all times, upon the outward stroke of cup B, ink will be drawn through pipe A above disk C and 75 will flow through slots E into the fountain. When this mode of operation is desired the disk C need have no movement upon pipe A and the upper end of pipe A is permanently open. This arrangement is shown in Fig- 80 ure 6.

I have shown and described grooves E upon the inner surface of the cup B, through which at the proper moment, communication is established between the fountain 1 and 85 the interior of the cup B, above the disk C. I am aware that the necessary passage for air around the disk C, can be established by apertures or constructions other than the specific grooves E, which I have shown and 90 described and I intend to cover such apertures or constructions by the use of the word grooves, the gist of the matter being that at the proper moment, movement of the cup establishes communication around or outside 95 the disk from one side of the disk to the other side.

I claim:

1. In a fountain pen, the combination of a fountain; a cup slidably mounted in the 100 rear end of the fountain and having suitable grooves opening inwardly; a pipe longitudinally mounted within the fountain, open at its front end to the air, and at its rear end communicating with the interior of the 105 cup above a disk; that disk, mounted upon the pipe at its rear end, within the cup and in frictional, air-tight engagement at its edges with the inner walls of the cup.

2. In a fountain pen, the combination of 110 a fountain; a cup slidably mounted in the rear end of the fountain and having suitable grooves upon its inner surface; a pipe longitudinally mounted within the fountain, open at its front end to the air and at its rear 115 end communicating with the interior of the cup above a disk; that disk, mounted for longitudinal movement upon the pipe at its rear end, within the cup and in frictional, air-tight engagement at its edges with the 120 inner walls of the cup, the disk moving to close the rear end of the pipe upon rearward movement of the cup and moving to open the rear end of the pipe upon forward movement of the cup.

3. In a fountain pen, the combination of 125 a fountain, a cup slidably mounted in the rear end of the fountain and having suit-

able grooves upon its inner surface; a pipe longitudinally mounted within the fountain, open at its front end to the air and at its rear end closed by a cap-stop and vented to the interior of the cup by a side aperture; a disk mounted for limited longitudinal movement upon the pipe at its rear end, within the cup and in frictional, air-tight engagement at its edges with the inner walls of the cup, the disk moving to close the pipe vent upon rearward movement of the cup and moving to open the pipe vent upon forward movement of the cup.

Signed at Boston, Massachusetts, this 21st day of September, 1921.

OLIVER MITCHELL.
